TORPEDO DEPTH CONTROL SYSTEM

August I. Keto, Los Altos, Calif., assignor to the
United States of America as represented by the
Secretary of the Navy

Application October 25, 1948, Serial No. 56,316

9 Claims. (Cl. 114—25)

1

This invention relates in general to a depth control system for torpedoes and is more particularly described as an electro-hydraulic system for proportional depth control.

In electrically propelled torpedoes it is often advantageous to use a proportional depth control system instead of the on-off system now being used. Motor operated rudder systems are not too satisfactory for higher speed torpedoes which travel at 40 knots and over, due to the rapidity with which the rudder must respond to changes in the angle or the depth signal. As no fluid pressure source is available in an electrical torpedo, such as high pressure air in standard air driven torpedoes, it becomes necessary to provide a system which is self contained, that will produce rapid positive proportional rudder motion with changes in the angle or depth signal.

An important object of the invention is to obtain positive proportional rudder motion with a 20 tilt or depth change in the travel of a torpedo.

Another object of the invention is to provide a fluttering motion of the rudder in controlling the torpedo depth, in which the amplitude is so small and the frequency so high that the torpedo body will not follow it.

A further object of the invention is to obtain quick action by high fluid pressure and without requiring a separate driving motor.

A still further object of the invention is to 30 provide an electrical depth control system which can be used on a torpedo with a homing head, with practically no change.

Other objects of the invention will appear in the specification and will be apparent from the accompanying drawing in which the figure is a diagrammatic view of an electro-hydraulic system for controlling the depth of electrically propelled torpedoes.

In carrying out this invention, magnetically controlled valve means and high pressure liquid pump means are mounted in a sealed container and they are controlled by two potentiometers, a vacuum tube and a relay, to produce a fluttering motion of the rudder independent of the torpedo body motion at any selected or predetermined balance point between the two potentiometers.

Referring now more particularly to the drawing, a sealed container 4 for liquid such as oil 6 has a plug 8 and a bellows 10 which act as a combined filling vent and an oil gage. In the container is a high pressure gear pump represented as having two gears 12 and 14 driven by a gear 16, shown for convenience of illustra-

2

tion as mounted upon a main drive shaft 18 with high pressure oil lines 22 and 24 leading from the gears (or pump) and outwardly through the container wall. Gear 16 is usually not mounted on the drive shaft, but is driven by it through a geared power take-off of any suitable known type.

Also located in the container are magnet and spring operated valves for controlling oil flow from the pumps: a magnet frame 26 has end recesses 28 and 30 connected by pipes 32 and 34 to the oil lines 22 and 24 respectively; each recess has openings in the frame, one opening 29 for the recess 28 and another opening 31 for the other recess 30 being at the same side of the frame from which an intermediate pivot bar 36 also extends. A magnet bar 38 is pivoted between its ends at the outer end of the bar 36 and at the ends of the magnet bar are round end valve plugs 40 and 42 adapted to seal conversely in and to close the openings 29 and 31 respectively.

Between the pivot bar 36 and the plug 40 is a coil spring 44 connected at one end to magnet bar 38 and at the other end to the magnet frame 26, and between the pivot bar and the plug 42 is a magnet core 46 secured to the magnet frame. Surrounding the core is a magnet winding 50 with conductors 52 and 54 leading therefrom through the container wall. When the winding 50 is energized the magnet bar 38 is rocked against the tension of the spring 44 closing the valve plug 42 in its opening 31 and moving the valve plug 40 to free its opening 29. When the winding is deenergized, the spring 44 reverses the movement of the bar 38, opening valve plug 42 and closing the valve plug 40.

Located outside of the sealed container and preferably near a rear bulkhead 56 is a closed cylinder 58 for a piston 60 movable therein and having a piston rod 62 extending from one end of the cylinder and through the bulkhead. A horizontal depth rudder 64 is pivoted on a block 66 and has an arm 68 pivotally connected to the end of the piston rod. A liquid packing 70 surrounds the rod in the bulkhead and a similar packing 72 for the rod is in the rear end of the cylinder 58.

Within the cylinder 58 the piston 60 is normally maintained in a position to hold the rudder 64 substantially horizontal with the piston centrally in a chamber 74 having a restriction partition 76 at the rear end spaced from the packing 72 and having an oil return pipe 78 connected thereto and to discharge into the con-

tainer 4. In practice the rudder is held at a slightly downward angle so as to maintain the torpedo at set depth on its run. With the rudder at its normal downward angle, the piston will be centrally located in the cylinder. Connected near one end of the chamber 74 is the high pressure line 22 and connected near the other end of the chamber is high pressure line 24.

High pressure fluid is thus supplied to the opposite ends of the chamber 74 tending to balance and maintain the piston in its central or normal position and the rudder horizontally. When either valve plug 40 or 42 is moved to open its valve, the corresponding pressure line 22 or 24 is relieved and the piston is pressed toward the relieved side by the opposite pressure line. Any surplus oil or any oil leakage is returned from the cylinder to the container 4 by the return pipe 78.

A piston potentiometer comprises a resistance 80 connected by conductors 82 and 84 with opposite terminals of a battery 86, and a contact maker 88 carried by and movable with the piston rod 62. Also connected to the terminals of the battery is a resistance 90 for a potentiometer which comprises a pendulum 92 mounted upon a transverse pivot 93 to swing fore and aft in a torpedo for controlling its depth or angle of inclination.

Extending from the contact maker 88 is a conductor 94 connected through a resistor 96 to the grid of an electronic tube 98. Extending from a contact maker 100 carried by the pendulum is a conductor 102 connected to the plate of the tube 98 and to one terminal of a battery 104. The other terminal of this battery is connected through a relay coil 106 for a circuit closer 108 in the magnet conductor 54, and is thence connected through conductor 110 to the cathode of the tube 98 to complete the relay coil circuit.

When the coil 106 is energized the circuit closer 108 completes a circuit through the magnet winding 50 and battery 112 by means of conductors 52 and 54. When the coil 106 does not receive enough current the circuit closer 108 does not operate or if the circuit has been closed, it is opened thereby.

In operation, a torpedo is fired and its main propulsion motor including the drive shaft 18 comes up to speed. The oil pump (or pumps) geared to the shaft builds up the required oil pressure which is supplied by the pipe lines 22 and 24 to both sides of the piston 60 tending to keep it centered longitudinally in the cylinder chamber 74.

When the torpedo is in steady running condition at its predetermined depth, the contact maker 100 of the pendulum potentiometer is essentially in mid position on the resistance 90 and the contact maker 88 of the piston potentiometer is also in mid position on its resistance 80. In this condition the torpedo rudder 64 will flutter through a small arc due to the on-off characteristics of the control system. For example: with the relay contact closer 108 in open condition, the magnet winding 50 is de-energized, the valve plug 42 is lifted from its opening 31, pressure is relieved in supply line 24, and the piston moves in the direction marked "open"; as the piston moves in this marked direction, the contact maker 88 on the piston rod 62 is moved therewith until the voltage on the grid of the electronic tube is such that sufficient current flows through the tube plate and the relay coil circuit to close the circuit closer 108; when

this circuit closer is closed, the circuit through the magnet winding 50 is closed, and this operates the magnet bar 38, opening the valve plug 40 and closing the valve plug 42; and the piston and piston rod are moved in the reverse or "closed" position.

With the piston motion in the direction marked "closed," the contact maker 88 on the piston rod is moved reversely until the voltage applied to the grid of the tube 98 is such that the current through the tube plate and relay coil circuit is so small that relay circuit closer 108 opens its circuit to the magnet winding 50, releasing the magnet bar to the influence and operation of its spring 44.

When the relay circuit closer for the magnet winding circuit is again "open," the cycle outlined is repeated rapidly and a fluttering movement of the rudder is produced. This fluttering movement is so small and the frequency is so high that the torpedo body will not follow it, and the movement is independent of the torpedo body motion.

A fluttering motion may be produced in a similar manner at any balance point between the two potentiometers. If the torpedo is tilted so that the contact maker 100 of the pendulum potentiometer is half way between the normal central position and one end of the resistance 90, the piston and cylinder assembly, acting under the fluid pressure, will move the contact maker 88 of the piston potentiometer to a corresponding position, and the fluttering action will be described about this point.

In recovery to a predetermined or set depth from a transient position or level, the pendulum contact maker 100 is moved along the potentiometer resistance 90 by the combined action of the angular deviation from the normal angle and by the depth deviation from the set depth. The piston or follower contact maker 88 is moved along its potentiometer resistance 80 by the action of the piston 60 as the fluid pressure system tends to maintain itself about the fluttering point. Thus the rudder is moved with a fluttering action rapidly from a hard over position to its normal running position.

This system can be used on a torpedo with a homing head, if a relay with normally closed contacts is placed in series in the magnet coil circuit. When a signal to the homing torpedo is correct, this relay with the normally closed contacts will open the circuit, de-energizing the magnet coil. With no power to the magnet coil the fluttering control action will cease, a hard up rudder will result and the torpedo will rise to attack.

Although this system has been described primarily as applied to depth control, it may also be adapted without substantial modification for steering a torpedo or vessel, keeping it automatically upon a set course, or varying the course by varying the position of the contact maker of the pendulum potentiometer. A rapid fluctuation of the rudder or a fluttering movement of small amplitude causes no corresponding fluctuations of the vessel, and only when the setting or positioning of the pendulum potentiometer produces a corresponding positioning of the piston potentiometer does a course changing movement of the rudder become effective.

Among the advantages of this system are: no sliding follower valves are required as used on the present type of air mechanisms; unit construction can be used, that is the depth mechanism

need not be mounted adjacent to the depth engine; the cylinder and piston assembly can be mounted with the oil reservoir as a unit or separately as desired; positive and proportional motion of the rudder is obtained with the tilt or depth change of the torpedo; the effect of friction in the rudder to the piston and cylinder assembly upon operation of the system is eliminated; and the assembly may be used on homing head torpedoes with only the addition of a relay switch.

Although this system has been described in detail it should be regarded as an illustration or example and not as a restriction or limitation, as various changes may be made in the construction, combination, and arrangement of the parts without departing from the spirit and scope of the invention.

I claim:

1. An electro-hydraulic depth control system for torpedoes, a rudder and a piston and cylinder engine for moving it, a pendulum potentiometer actuated by fore and aft inclination of the torpedo, fluid pressure means for moving the piston in reverse directions and including magnetic valve means and an energizing circuit therefor including normally open contacts with a relay for closing them, an electronic device and a circuit from the potentiometer including the relay and the device to successively energize and deenergize the relay, and a piston potentiometer connected in parallel with the pendulum potentiometer and including a contact maker movable with the piston and connected to the electronic device to vary the current through the relay and operating the relay contacts to vary the magnetic valve means and thereby to produce a rapid fluttering action of the piston and of the rudder.

2. In an electro-hydraulic depth control system for torpedoes, a rudder and a piston and cylinder engine for operating it, fluid pressure supply means for the engine, magnetic valve means to control the fluid pressure means, a pendulum potentiometer and a piston potentiometer connected in parallel, a relay for controlling the magnetic valve means, and an electronic device connected to the relay and to the potentiometers separately and operative to vary current to the relay for operating the valve means and to move the piston potentiometer correspondingly for any change of the pendulum potentiometer.

3. In an electro-hydraulic depth control system for torpedoes, a rudder and a piston and cylinder engine for operating it, fluid pressure supply means for the engine, magnetic valve means to control the fluid pressure means, a pendulum potentiometer and a piston potentiometer connected thereto, a relay connected to and for controlling the magnetic valve means, and an electronic tube having a grid connected to the piston potentiometer, a plate connected to the pendulum potentiometer, a cathode connected to the relay, and the tube being operative to rapidly energize and de-energize the relay for any set position of the pendulum potentiometer to cause a rapid movement of the piston and the rudder for any position of the pendulum potentiometer.

4. In an electro-hydraulic depth control system for torpedoes, a rudder and a piston and cylinder engine for operating it, fluid pressure supply means for the engine, magnetic valve means to control the fluid pressure means, a pendulum potentiometer and a piston potentiometer,

ometer, a relay for controlling the magnetic valve means, and an electronic tube having a plate connected to a variable contact maker of the pendulum potentiometer, a grid connected to a variable contact maker of the piston potentiometer, and a cathode connected to the relay, the tube connections operative to produce rapid fluctuations of current to the relay causing a fluttering action of the piston and rudder of small amplitude at relatively different locations depending upon the position of the pendulum contact maker.

5. In a rudder control system for torpedoes and the like, a rudder and a piston and cylinder engine for operating it, fluid pressure supply means for the engine, magnetic valve means to control the supply means, a positioning potentiometer, a following potentiometer operated by the engine and movable with the piston, a relay for controlling the magnetic valve means, and an electronic device having a plate connected to the positioning potentiometer, a grid connected to the follower potentiometer, and a cathode connected to the relay, the arrangement being that any variation of the positioning potentiometer will cause the relay to operate the valve means to change fluid pressure applied to the engine, moving the piston and changing the follower potentiometer to correspond with the position of the positioning potentiometer and changing the current in the electronic device to cut off the relay, and repeating this cycle with rapid movements of small amplitude of the piston and rudder in any set position after the follower potentiometer is changed to correspond with the set position of the positioning potentiometer.

6. In a rudder control system for torpedoes and the like, a rudder and a piston and cylinder engine connected thereto for operating it, fluid pressure supply means connected to opposite sides of the piston near the ends of the cylinder electro-responsive valve means for controlling the excess of pressure on one side or the other of the piston, a circuit including closable contacts for operating the valve means, a relay for opening and closing the contacts, a potentiometer variable by the movement of the piston, a positioning potentiometer, and an electronic device having parts connected to the positioning potentiometer, to the piston potentiometer, and to the relay, with the arrangement that a current is set up which will actuate the relay to close the contacts and this will close a circuit to produce actuation of the valve means to operate the piston and its potentiometer in a manner to reduce the voltage in the device and then to reduce current in the device to the relay to open the contacts, and to repeat this cycle in rapid fluctuations of small amplitude.

7. In a rudder control system for torpedoes and the like, said control system having a rudder and a piston rod connected thereto for operating it, a piston on the rod movable in a cylinder, high pressure fluid supply pipes connected at opposite ends of the cylinder, pumping means for supplying fluid through the pipes under pressure to both ends of the cylinder, and a valve in connection with each pipe comprising a movable valve plug; a centrally pivoted magnet bar to the ends of which the valve plugs are connected for movement in opposite directions to close one valve and to open the other, an electro-magnet stationed at one side of the magnet bar pivot to operate the bar in one direction, a spring stationed at the other side of said pivot to operate

the bar in the reverse direction, and means to rapidly energize and de-energize the electro-magnet to produce a rapid fluctuation of the bar.

8. In a rudder control system for torpedoes and the like, said control system having a rudder and a piston rod connected thereto for operating it, a cylinder and a piston therein connected to the rod, and high pressure supply pipes connected to the cylinder at opposite ends; a closed fluid container, pumping means housed in the container and being operative to draw fluid from the container and deliver it through the pipes under pressure to both ends of the cylinder, a magnet frame also housed in the container, said frame having valve recesses and openings at spaced locations connected to the pipes, valve plugs engageable in the recesses and movable outwardly to relieve pressure in the pipes, a magnet bar adjacent to the magnet frame, being pivoted at its central part on said frame and connected at its ends to the plugs, an electro-magnet mounted on the frame to rock the bar in a direction to engage one plug and to free the other, and spring means mounted between the frame and magnet bar, being opposed to the magnet pull to engage the other said plug and to free the first one, and means to alternately energize and de-energize the electro-magnet to rock the bar rapidly in opposite directions.

9. In a rudder control system for torpedoes and the like, said control system having a rudder and a piston rod connected thereto for operating it, a cylinder into which the rod extends having a piston chamber and a relief chamber, and a piston on the rod in the piston chamber; a sealed container, a tubular connection between the relief chamber and the container, a double high pressure fluid pump in the container, a pair of pipes connected to the pump and extending to opposite ends of the piston chamber, relief means for each

5
10
